UNITED STATES PATENT OFFICE

141,002

DESIGN FOR A DOLL

Henrietta Wilcox, Brecksville, Ohio

Application November 13, 1944, Serial No. 116,310

Term of patent 7 years

(Cl. D34—4)

To all whom it may concern:

Be it known that I, Henrietta Wilcox, a citizen of the United States, residing in the city of Brecksville, county of Cuyahoga, and State of Ohio, have invented a new, original, and ornamental Design for a Doll, of which the following is a specification, reference being had to the accompanying drawing, forming a part thereof.

I claim:

The ornamental design for a doll, substantially as shown.

HENRIETTA WILCOX.
